JACK

Filed Dec. 7, 1926

INVENTOR.

CARL E. RICE

BY

C. E. Rice
ATTORNEY.

UNITED STATES PATENT OFFICE

CARL E. RICE, OF TOPEKA, KANSAS

JACK

Application filed December 7, 1926. Serial No. 153,069.

My invention relates to improvements in jacks.

The object of my invention is to provide a jack that is attached to the axle of the vehicle.

A further object of my invention is to provide a jack that will function without placing the upper end beneath the axle.

A still further object of my invention is to provide a jack that can be operated under unusual conditions such as in mud, sand or the like when the axle is in close proximity to the surface rendering it difficult to place an ordinary jack between the axle and the ground.

A still further object of my invention is to provide a jack that can be attached adjacent to one or all of the wheels of the vehicle.

These and other objects will hereinafter be more fully explained.

Referring to the drawings:

Fig. 1 is an elevation of the jack as applied, parts removed for convenience of illustration.

Fig. 2 is a transverse view of Fig. 1, partly in section for convenience of illustration.

Fig. 3 is a transverse view of the screw attaching means.

Fig. 4 is a side view of the drum and housing showing the spring actuating means for the drum.

Fig. 5 is a view showing the jack in its operative position on the rear axle of an automobile.

Fig. 6 is a transverse view of the pawl shown in Fig. 1.

The mechanism herein disclosed consists of a clamp 1 the form of which would apply to the rear axle of an automobile; other forms will be made to suit the shape of other axles. The said clamp is made in two parts A and B, the said parts being rigidly connected by means of bolts 2 engaging through apertures in the outer turned ends of the clamp. Integral with member B is a hanger 3 to which

are pivotally connected the expanding and retracting members 4 by means of a bolt 3', the said members having a block 5 pivotally engaging in the upper ends thereof and removable by means of a member 6 which is rigidly attached to the members 4 as shown

in Fig. 3. The said blocks have apertures 7 concentrically positioned and threaded to receive a threaded screw 8. The threads on said screw are right and left handed so that when turned the members 4 will move to or from each other.

On the opposite ends of the members 4 are pivotally connected a series of bars 4', and at the lower end thereof pivotally connected is a foot plate 4" as a bearing on the ground. As an actuating means for the said screw I have centrally positioned a drum 9 having two peripheral grooves 10 as shown in Fig. 1. The said grooves are adapted to receive cords 11 and 11' as rotating means therefor for the purpose hereinafter described.

Housed within the drum is a pair of toothed members 12, the said members formed to rigidly engage at their center the square portion C of the screw member 8. Rotation of the toothed members 12 is thereby transmitted to the screw 8. The teeth on said members extend in opposite directions as shown in Fig. 2 to engage with a pawl 13 adapted to alternately drive the screw in opposite directions as hereinafter described.

The drum is hollow and has one side removed as a convenient means to assemble or remove the toothed members. The said drum is inclosed by a housing 14 in which it is rotatably carried on the said screw 8, the housing being prevented from rotation by means of a leg 15 having a slot 16 centrally and longitudinally positioned as shown in Fig. 1, the said slot engaging with a screw 17 which threadedly engages in the head of the bolt 3'. By this arrangement the drum is free to move vertically when the members 4 are expanded and retracted. The drum being free to rotate on the screw is tensioned in a certain position by means of springs 18, the ends of which are attached to the housing as at D. The opposite ends are attached to the drum as at E. Note that the springs extend in opposite directions so that the tension thereof will retract the drum after being rotated by pulling the cords 11 and 11'. The said cords are wound on the drum in opposite directions connecting with the pin 19 transversely ex-

tending from the pawl, the pawl being pivotally connected to the drum by means of a pin 20 so that by drawing either of the cords the pawl will be rocked to engagement with its respective toothed member rotating the screw accordingly. It will be understood that the cords when drawn will slip on the face of the drum sufficient to rock the pawl to engagement preparatory to rotating the screw in the preferred direction. When drawn to the full extent of the revolution and release the springs will cause the drum to retract as heretofore described. By repeating the pull on the same cord the screw 15 will revolve in one continuous direction.

As a means to actuate the pawl from engagement with both of the toothed members simultaneously I have provided springs 21 to engage therewith as shown in Fig. 2, the said 20 springs being rigidly attached to the peripheral wall of the drum to equally tension on both ends of the said pawl.

To operate the mechanism herein disclosed it will be assumed that the automobile or 25 other vehicle to which the jacks are attached is mired, with the axle so near the ground that it would be impossible to place an ordinary jack such as commonly used, but when equipped with the jack as herein set forth, 30 such difficulty will be obviated.

To engage, the cord 11 is drawn outward to the position shown at F in Fig. 5. To disengage, the cord 11' will be drawn outward which will retract the toggle members as 35 shown at G in Fig. 5.

The clamping means for the jack being constructed as shown will render it possible to rock the jack to a horizontal position above the axle. However it is designed that the foot 40 will retract to a level with the under side of the axle.

When applied to the front axle which is of rectangular shape semi-circular members could be placed on either side of the axle permitting the jack to rock to a horizontal position in like manner to that of the rear.

Such modifications may be employed as lie within the scope of the appended claims.

Having thus described my invention, what 50 I claim as new and desire to secure by Letters Patent is:—

1. In a jack, a right and left hand threaded screw having a square portion centrally positioned on the screw, a pair of toothed discs 55 fitted snugly on the square portion of the screw and rotatable therewith, the teeth of the discs extending in opposite directions, a hollow drum having one side removed, the drum rotatable on the screw and housing the toothed members concentrically, a toothed pawl pivotally connected and positioned in the drum, and a tensioning spring for each 60 end of the pawl respectively, the toothed members of the pawl positioned on a plane 65 with their respective toothed discs and means

to rock the pawl simultaneously with the rotation of the drum to turn the said screw in either direction, a lazy tong having a foot plate pivotally carried on the outer or lower end, the two opposite end portions of the lazy tong having a pivotally mounted block in each thereof, the blocks threadedly engaging on their respective end portions of the screw by which means the lazy tong is raised or lowered by the rotation of the drum, a housing 70 for the said drum, the drum rotatably carried on the screw, and in the housing a leg outwardly extending and connected to the periphery of the housing the leg being slotted to slidably engage on a headed screw 75 positioned in the top joint of the lazy tong by which means rotation of the said housing is prevented, leaf springs having one end attached to the housing and the other to the drum as retracting means for the drum as 80 the screw is turned.

2. In a jack, a jack of the class described comprising a lazy tong and a right and left hand threaded element to expand and contract the lazy tong, a pair of toothed wheels 90 rigidly attached to the center of the screw, the teeth of said wheels extending in opposite directions, and a drum housing the toothed wheels and having annular grooves in the periphery thereof, the drum rotatable 95 on the screw, and a pawl having toothed members extending in opposite directions and positioned to engage with each of said toothed wheels respectively, the pawl pivotally carried by the drum and having a pin outwardly 100 extending to receive cords, cords wound on the drum in opposite directions as rotating means therefor, the cords being attached to the pin of the pawl as rocking means for the pawl simultaneously with the rotation of the drum, a housing for the said drum, the drum 105 rotatable on the screw in the housing and the housing having a leg to engage with the lazy tong to prevent rotation while the drum is being rotated, springs attached to the drum and the housing as retracting means for the drum to a normal position for the pawl's 110 engagement with the toothed wheels.
